MATTRESS STRUCTURE

Max Koenigsberg, Highland Park, Ill., assignor to The Englander Company, Inc., Chicago, Ill., a corporation of Delaware

Application September 30, 1955, Serial No. 537,730

3 Claims. (Cl. 5—345)

The present invention relates to a novel mattress, and more particularly to a novel foam rubber mattress structure.

Foam rubber mattresses heretofore commercially available have usually consisted of a single pad of foam rubber covered by a suitable fabric or ticking. In order to provide such a mattress with the desired softness and luxurious feel, the rubber pad is made relatively thick. However, as the thickness of the foam rubber pad is increased, the pad becomes laterally unstable so that it may quiver in a jelly-like manner.

It is an important object of the present invention to provide a novel foam rubber mattress construction which is sufficiently thick so that the desired softness and luxurious feel is obtained and which is constructed so as to substantially reduce the undesirable lateral instability or jelly-like characteristics of relatively thick foam rubber mattresses heretofore proposed.

A more specific object of the present invention is to provide a novel foam rubber mattress structure of the above described type which is formed so as to restrain peripheral and internal portions thereof against spreading laterally or outwardly under the weight of a person lying on the mattress so that the mattress is firmer and more stable while still having the desired softness.

Other objects and advantages of the present invention will become apparent from the following description and the accompanying drawings wherein:

Fig. 1 is a perspective view of a mattress structure embodying the principles of the present invention;

Fig. 2 is an exploded perspective view on a reduced scale of the internal elements of the novel mattress structure;

Fig. 3 is an enlarged fragmentary sectional view taken along line 3—3 in Fig. 1; and

Fig. 4 is an enlarged fragmentary elevational view of a corner portion of the novel mattress structure.

Referring now more specifically to the drawings where like parts are designated by the same numerals throughout the various figures, a mattress structure 10 embodying the principles of the present invention includes a pair of pads 12 and 14 formed from foam rubber or the like. The foam rubber pads may be formed in any known manner and may be provided with air pockets 16 and 18, if desired. The combined thickness of the pads 12 and 14 may be varied but should be sufficient to provide the mattress with the desired softness and luxurious feel.

In accordance with the present invention the lateral stability or firmness of the interior portions of the mattress is substantially improved by providing a sheet 20 between the pads 12 and 14. The sheet 20 is formed from any suitable flexible material or fabric which is relatively unstretchable as compared with the foam rubber pads, and the sheet is adhesively secured as indicated at 22 and 24 to the inner surfaces of the pads 12 and 14 so that the pads and the sheet are combined as a unit. The relatively unstretchable sheet serves to restrain the

interior surfaces of the pads and the portions of the pads adjacent the interior surfaces against lateral expansion while at the same time, the flexible sheet does not unduly impair the softness of the pads.

5 The foam rubber pads are covered with fabric panels or ticking which provide the mattress with the desired pleasing appearance and also serves to confine the peripheral surfaces of the pad. More particularly, the mattress cover comprises top and bottom fabric panels 26 and 28, 10 and a pair of fabric strips 30 and 32 which extend entirely around the edge of the mattress. As shown in Fig. 3, the peripheral edge of the panel 26 substantially abuts the upper edge of the panel 30, and a binding strip 34 is placed over these edges and the strip and edges are sewn together by stitches 36. Preferably, the edges of the panels are folded reversely as shown, and the stitches are directed through the double thicknesses provided by the folds so as to reduce any possibility of the panels becoming torn. It should be noted that the stitches 36 extend 15 through the upper, peripheral corner of the pad 12 so that the fabric panels are held in fixed relationship with respect to the foam rubber pad. The bottom panel 28 is connected with the edge panel or strip 32 along a seam which includes a binding strip 38 and stitches 40 which are formed and positioned in the same manner as the binding strip 34 and stitches 36 described above.

The fabric panel 20 which is disposed between and adhesively secured to the foam rubber pads 12 and 14 has its peripheral edge secured to adjacent edges of the 20 strips or panels 30 and 32. As shown in Figs. 3 and 4, a binding strip 42 is placed over the adjacent edges of the strips 30 and 32, which edges are reversely folded to reduce any possibility of tearing. The peripheral edge of the panel 20 extends between the folded edges of the 25 panels 30 and 32, which edges and the binding strip 42 are secured together by stitches 44. With this structure, the panel 20 serves to prevent the panels 30 and 32 from stretching outwardly when a load is on the mattress, and the panels 30 and 32, in turn, retain the foam rubber pads 30 against undue lateral expansion.

From the above description, it is seen that the present invention has provided a foam rubber mattress structure which may be easily and economically fabricated so as to have sufficient depth to provide the desired softness and luxurious feel without having undesirable lateral instability. More specifically, it is seen that the present invention has provided a novel mattress structure comprising a plurality of foam rubber pads confined by and secured to flexible but relatively unstretchable fabric 45 panels in the manner which substantially improves the lateral stability of the foam rubber pads without unduly impairing the desired softness or feel of the mattress.

While the preferred embodiment of the present invention has been shown and described herein, it is obvious that many structural details may be changed without departing from the spirit and scope of the appended claims.

The invention is claimed as follows:

1. A mattress structure comprising a cushion unit including a plurality of superposed pads of foam rubber and the like each having a plurality of air pockets having open ends at a surface thereof facing an adjacent surface of another pad, and a flexible relatively unstretchable fabric sheet disposed between and adhesively secured substantially to entire adjacent surfaces of adjacent pads 60 around the open ends of the air pockets to increase lateral stability of the pads, and cover means including side portions overlying opposite sides of said unit and an edge portion surrounding a peripheral edge of said unit, said fabric sheet having its peripheral edge stitched to said cover means edge portion between said side portions for restraining said edge portion and peripheral edges of said pads against lateral expansion when a load is placed on 65 70

the mattress, and stitch means connecting adjacent margins of said side portions and said edge portion and also extending through adjacent outer peripheral corner portions of opposite outermost pads for retaining the cover means and the pad in substantially fixed relationship and for further restraining lateral expansion of the pads.

2. A mattress structure comprising a cushion unit including a plurality of superposed pads of foam rubber and the like each having a plurality of spaced air pockets aligned with air pockets in an adjacent pad, which air pockets have open ends at adjacent surfaces of adjacent pads, and a flexible relatively unstretchable fabric sheet disposed between and adhesively secured substantially to entire adjacent surfaces of adjacent pads around the open ends of the air pockets to increase lateral stability of the pads, cover means including side portions overlying opposite sides of said unit and an edge portion surrounding a peripheral edge of said unit, said fabric sheet being connected to said cover means edge portion between said side portions for restraining said edge portion and peripheral edges of said pads against lateral expansion when a load is placed on the mattress, and means securing peripheral corners of said cover means between said side portions and said edge portion to peripheral outer corners of opposite outermost pads of said unit to retain said cover means and said pads in substantially fixed relationship and further to restrain lateral expansion of said pads.

3. A mattress structure comprising a cushion unit including a plurality of superposed foam rubber pads, and flexible relatively unstretchable fabric sheet means disposed between and adhesively secured to substantially

entire adjacent surfaces of adjacent pads to increase lateral stability of the pads, and cover means including a pair of fabric side panels overlying opposite sides of said unit and a pair of complementary edge panels surrounding a peripheral edge of said unit, stitch means connecting adjacent margins of said edge panels and a peripheral margin of said fabric sheet means for retaining said edge panels and peripheral edges of said pads against lateral expansion when a load is placed on the mattress, and stitch means connecting peripheral margins of said side panels and adjacent margins of said edge panels and also extending through peripheral corner portions of opposite outermost pads of said unit for retaining said cover means in substantially fixed relationship with respect to said pads and for further restraining lateral expansion of the pads.
